UNITED STATES PATENT OFFICE.

DANIEL SNYDER AND ELLWOOD IVINS, OF PHILADELPHIA, PENNSYLVANIA,
ASSIGNORS TO SAID IVINS AND LEWIS D. ZEIGLER, OF SAME PLACE.

BUTTON-HOLE CUTTER.

SPECIFICATION forming part of Letters Patent No. 239,279, dated March 22, 1881.

Application filed January 10, 1881. (No model.)

To all whom it may concern:

Be it known that we, DANIEL SNYDER and ELLWOOD IVINS, citizens of the United States, residing in Philadelphia, Pennsylvania, have 5 invented an Improved Button-Hole-Cutting Attachment for Shears or Scissors, of which the following is a specification.

Our invention relates to a button-hole-cutting device adapted to be attached to one 10 blade of a pair of shears or scissors, and to co-operate with the other blade in forming the button-hole, the objects of our invention being to provide for the secure attachment of the cutting device to the blade of the scissors 15 or shears in any desired position, and to accurately govern the size of the button-hole cut by the device.

In the accompanying drawings, Figure 1 is a perspective view of a pair of scissors with 20 our improved button-hole cutter applied thereto, and Fig. 2 a vertical section of the cutting device drawn to an enlarged scale.

A is a plate, preferably of sheet-steel, and having a sharpened upper edge, *a*, terminating 25 at the end in a pointed projection, *b*. To this plate, some distance below the cutting-edge of the same, is secured the upper edge of a plate, B, the lower portion of which is confined to the plate A by means of a thumb-screw, *d*, the threaded stem of the latter passing 30 freely through an opening in the plate B, and being adapted to a threaded opening in the plate A; or, if desired, a threaded stem and thumb-nut may replace the thumb-screw. 35 The plates A and B are so shaped as to fit to one of the blades, D, of a pair of scissors, as shown in Fig. 1, and are drawn together by tightening the screw *d*, so as to firmly clamp the blade D; or the screw *d* may be loosened, 40 in order to permit the adjustment of the plate A to a different position on said blade D.

F is a slotted bar, the upper end, *e*, of which is inclined and bent inward, so as to form a stop for the blade E of the scissors in cutting, the adjustment of the inclined edge of 45 the bar in respect to the cutting-edge *a* of the plate A governing the width of the button-hole produced by the combined action of said plate and the blade E of the scissors. (See Fig. 1.) The slotted bar is guided by the stem 50 of the screw *d*, and by a stud, *f*, the screw *d* serving to secure the bar in any vertical position to which it may have been adjusted in respect to the plate A. The pointed projection *b* on the plate A provides a means of accurately determining the location of the cut made by said plate, the point of the projection being thrust through the fabric before the cut is made.

We claim as our invention—

1. A button-hole-cutting attachment for 60 scissors or shears, in which the cutting-plate, adapted to be secured to one blade of the scissors or shears, is combined with an adjustable gage-bar, adapted to act in conjunction with 65 the other blade, as specified.

2. The combination of the cutting-plate A, the clamping-plate B, and the slotted gage-bar F, with the screw *d*, serving to confine the bar and clamp the two plates together, as 70 specified.

In testimony whereof we have signed our names to this specification in the presence of two subscribing witnesses.

DANIEL SNYDER.
ELLWOOD IVINS.
